United States Patent Office.

HENRY OCORR, OF SHEBOYGAN, WISCONSIN.

Design No. 4,742, dated March 28, 1871.

DESIGN FOR CHAIRS.

The Schedule referred to in these Letters Patent and making part of the same.

To whom it may concern:

Be it known that I, HENRY OCORR, of Sheboygan, in the county of Sheboygan and State of Wisconsin, have invented a new and original Design for Chairs, of which the following is a specification, reference being had to the accompanying drawing, which represents in perspective a chair designed in accordance with my invention.

The design represented relates more particularly to the base or lower part of the chair.

On each side the piece A, curved and shaped as shown, forms the two legs and the top rail of the base.

The pieces A on each side are connected together at the top in front and rear by rails B, and on the sides the legs are stiffened by the lower curved pieces C, the base when thus made presenting the general appearance shown in the drawing.

Upon the base is supported the chair-seat and back E F, the conformation of which is plainly indicated in the figure.

What I claim as my invention, and desire to secure by Letters Patent, is—

1. The design for a chair, substantially as herein shown and described.
2. The design for the base or lower part of a chair, substantially as shown.

In testimony whereof I have hereunto set my hand in the presence of two subscribing witnesses.

HENRY OCORR.

Witnesses:

M. BAILEY,
C. B. NOTTINGHAM.
